SPRING PRESSED WINDOW STOP
CONSTRUCTION

Roy T. Axe, Syracuse, N. Y., assignor to the O. M. Edwards Company Inc., Syracuse, N. Y., a Corporation of New York

Application October 10, 1931. Serial No. 568,127

11 Claims. (Cl. 189—73)

This invention relates to window constructions, particularly for railway cars, motor busses, and the like, and has for its object, a particularly simple and adjustable means for applying a predetermined pressure to the window stop for holding the sash tight against rattling without binding the sash in its guide.

The invention consists in the novel features and in the combinations and constructions hereinafter set forth and claimed.

In describing this invention, reference is had to the accompanying drawings in which like characters designate corresponding parts in all the views.

15 Figure 1 is a fragmentary elevation of a window construction embodying this invention.

Figure 2 is an enlarged, sectional view on line 2—2, Figure 1.

Figure 3 is a fragmentary inner face view of 20 one of the stops.

Figure 4 is a detail view of the screw threaded socket for receiving the adjusting screws for the adjustable stop.

Figure 5 is a fragmentary view of one of the 25 outer stops.

In window constructions, such as are used in motor busses and the like, the window sashes must be held sufficiently tight to prevent rattling, and at the same time be capable of being raised 30 and lowered without binding.

At the outset, window stops can be arranged so as to hold the sashes, but during use, because of dust and the like finding its way into the sash guide and there being no place for the 35 dust to work out, the sashes become difficult to raise and lower.

The principal feature of this invention is means by which this condition can be relieved 40 quickly by adjusting one of the window stops, usually the inner stop.

1 designates the usual upright frame members or posts of a window frame.

2 and 3 designate respectively outer and inner 45 stops which form a guide for the stiles 4 of the sash 5, one of these stops, usually the inner stop, being spring pressed with a predetermined spring pressure against the sash.

One feature of the invention is the adjusting of 50 this spring pressure, or adjusting the thrust or pressure of the adjustable or inner stop against the sash, so that the sash will work without rattling and without binding.

The outer stop 2 which, in this embodiment of 55 my invention, is not adjustable, may be of any suitable form, size and construction, it being here

shown as right angular in cross section with one flange forming the outer stop, and the other flange 7 seating against the post.

The adjustable inner stop 3 is channel shaped 60 in cross section with the bottom 8 of the channel lapping the inner face of the frame member or post 1, that is, the face toward the interior of the vehicle, with the side flanges of the channel spaced apart from the side faces of the frame member or post 1, and with inturned flanges 9 65 at the entrance of the channel formation, which flanges thrust against the stiles 4 of the sashes.

The stop 3 is thus double construction and angular in cross section, open at one side, and with the open side toward the frame member or post 1. The stop 3 is secured to the post or frame member 1 so as to be yieldingly pressed against 70 the sash or sashes by springs, and the tension of the springs adjusted to adjust the thrust or grip 75 of the stop 3 on the sash or sashes.

10 designates springs located within the stop 3 on opposite sides of the post or frame member 1 and interposed between the flanges 9 and the opposite ends of a spring abutment or plate 11 extending transversely of the outer face of the 80 frame member or post 1 under and spaced from the bottom flange 8 of the stop 3. The abutment is here shown as slidably mounted upon studs 12 secured at like ends to the bottom 8 of the channel 85 formation, and at their other ends extend into the flanges 9, and the springs 10 encircle said studs.

The means for securing the abutment to the frame member or pillar 1 and adjusting it to adjust the tension of the springs 10 comprises a 90 member as a screw 14 extending through the bottom 8 of the channel shaped stop 3 through the abutment and threading into the frame member or post 1, the screw having its head 15 thrusting against the outer face of the abutment 11, 95 so that as the screw is tightened, the abutment will be moved inwardly toward the frame member or post 1, thus compressing the springs so that they act with greater force against the flanges 9 and thus thrust the stop 3 or the flanges 9 there- 100 of with greater force against the sash or sashes. Loosening of the screw lessens the thrust or force of the springs against the flanges 9. Owing to the mounting of the abutment 11 with the screw located between the ends of the abutment and between the springs, it has a rocking or equalizing 105 action against the upper ends of the springs 10.

For the end windows, where the pillar or frame member 1 does not separate two window constructions, any suitable member may be substituted for 110

one of the sash stiles for the stops to thrust against.

The screws 14 preferably thread into a longitudinally split threaded socket provided in the frame member or post 1. 16 designates the socket split longitudinally at 17, and having a face plate 18 at its outer end overlying the face of the frame member or post 1 and secured thereto in any suitable manner, as by screws 19. The socket is first 10 threaded and then split, and then the sections thereof compressed inwardly so that when the screw is turned in the socket, the sections of the socket grip the screw and hold it from unintentional turning. There may be one or more abutments 11 and companion springs 10, and adjusting screws 14 spaced along the outer stop, and there are usually three of such abutments near the upper and lower ends and midway between the ends of the stop.

20 The heads of the screws 14 are preferably formed so that a special tool, wrench, or screw driver, is required to operate them, whereby the screws can be adjusted only by authorized persons. As shown, the heads of the screws are formed with spaced holes 20 requiring a tool with similarly spaced prongs.

The inturned flanges 9 of the stop 3 are preferably provided with wear strips 21 for engaging the sashes, which strips are secured thereto in 30 any suitable manner, as by rivets 22. The stop 3 is usually formed of steel and finished to represent wood, or in any other manner, and the wear strips are brass to coact with sheet metal hollow stiles of the sashes. The angular stops 35 2 are also preferably brass.

25 is a facing or trim strip for the outer side of each post 1, these being in the general form of a channel embracing the post with the bottom of the channel against the post, and the side flanges 26 lapping the sash sides of the post and provided with angular flanges 27 lapping the flanges 28 of the angular outer stop 2. The facing strip 25 is permanently secured to the post as by screws 29, and is not intended to be removed. It is usually steel enamelled, painted, or otherwise finished.

Usually, the stops 2 are secured to the post 1 rather than to the facing strip 25, and are secured to the post, as by screws 30, extending 50 through the flange 7 of the stop 2, which flange 7 seats against the post.

The flanges 7 of each of the stops 2 are provided with holes 32 for receiving the bolt of a sash holder or lock 33, which bolt moves through 55 the edges of the sashes, the post 1 being provided with bores 34 alined with the holes 32 for receiving the ends of the bolts.

The sash locks or holders 33 may be of any 60 suitable construction, and there is usually a sash lock or holder at the lower corners of each sash. Each includes a finger lever 36 which is connected, through any well known mechanism, to the bolt.

65 In operation, when the sash is first inserted, the inner stop 3 is adjusted by turning the screws 14. After the sash has been in use and the sash guide fills more or less with dust, or other material, tending to cause it to bind with such initial adjustment, the screws 14 can be unscrewed slightly, as a quarter or half turn, thus relieving the tightness.

What I claim is:

75 1. In a window construction, the combination of a window frame, inner and outer stops form-

ing a sash guide, a sash movable in the guide, one of the stops being formed with a recess, a spring abutment extending into the recess, spring means interposed between the abutment and the stop tending to thrust the stop against the sash, and means acting on the abutment and connected to the frame for securing the abutment to the frame and adjusting the abutment to tension the spring means. 80

2. In a window construction, the combination 85 of a window frame, outer and inner stops forming a sash guide, and a sash movable in the guide, one of the stops being formed angular in cross section with its open side toward the frame, a spring abutment carried by the frame and extending into the interior of the angular stop and opposed to the wall of the stop thrusting against the sash, a spring located in the angular stop and thrusting against the abutment and against said wall, and means for securing the abutment to the frame and adjusting the same to adjust the spring. 90

3. In a window construction, the combination 95 of a window frame, outer and inner stops forming a sash guide, and a sash movable in the guide, one of the stops being formed angular in cross section with its open side toward the frame, an abutment carried by the frame and extending into the interior of the angular stop and opposed to the wall of the stop thrusting against the sash, a 100 spring located in the angular stop and thrusting against the abutment and against said wall, and means for securing the abutment to the frame and adjusting the same to adjust the spring, said angular stop having a wall covering the abutment 105 and provided with an opening through which said means is operable.

4. In a window construction, the combination 110 of a window frame, inner and outer stops on the frame forming a sash guide, and a sash movable in the guide, one of the stops being angular in cross section and having an inwardly extending flange for engaging the sash and also a flange opposed to the former flange and lapping the outer 115 face of the frame, an abutment arranged in said angular stop and extending into a position opposed to and spaced from the flange which engages the sash, a spring interposed between the abutment and the flange which engages the sash, and means extending through the flange lapping 120 the outer face of the frame and thrusting against the abutment and coacting with the frame for securing the abutment to the frame and the stop to the abutment. 125

5. In a window construction, the combination 130 of a window frame, inner and outer stops on the frame forming a sash guide, and a sash movable in the guide, one of the stops being angular in cross section and having an inwardly extending flange for engaging the sash and also a flange 135 opposed to the former flange and lapping the outer face of the frame, an abutment arranged in said angular stop and extending into a position opposed to and spaced from the flange which engages the sash, a spring interposed between the abutment and the flange which engages the sash, and means extending through the flange lapping 140 the outer face of the frame and thrusting against the abutment and coacting with the frame for securing the abutment to the frame and the stop to the abutment, said means being adjustable for 145 adjusting the tension of the spring.

6. In a window construction, the combination 150 of a window frame member having inner and outer stops forming a sash guide, and a sash mov-

- able in the guide, one of the stops being in the form of a channel in cross section and embracing the frame member with the bottom of the channel formation covering the frame member, said stop having inturned flanges at the entrance of the channel formation, an abutment opposed to the bottom of the channel formation and having its end portions opposed to said flanges, springs interposed between the end portions of the abutment and said flanges, and securing means extending through the bottom of the channel formation and into the frame member, said means thrusting against the abutment. 80
7. In a window construction, the combination of a window frame having inner and outer stops forming a sash guide, and a sash movable in the guide, one of the stops being in the form of a channel in cross section and embracing the frame member with the bottom of the channel formation covering the frame member, said stop having inturned flanges at the entrance of the channel formation, an abutment opposed to the bottom of the channel formation and having its end portions opposed to said flanges, springs interposed between the end portions of the abutment and said flanges, and a screw extending through the bottom of the channel formation and through the abutment and threading into the frame member, the screw having a head thrusting against the abutment. 85
8. In a window construction, the combination of a frame comprising a post having inner and outer stops on opposite sides thereof forming sash guides, sashes movable in the guides, one of the stops on each side of the post being angular in cross section and having one of its flanges against the side of the post, and the other stop being in the general form of a channel embracing the post and extending on opposite sides thereof with the bottom of the channel forming a facing for the post, and the flanges of the channel extending on the sash guides of the post and formed with inturned flanges forming like sides of the sash guides and opposed to the other stop, means for securing the channel-shaped stop to the post, and a channel-shaped facing strip embracing the opposite side of the post to that on which the channel-shaped stop is located, and having flanges overlying the other flanges of said angular stops. 90
9. In a window construction, the combination of a frame comprising a post having inner and outer stops on opposite sides thereof forming sash guides, sashes movable in the guides, one of the stops on each side of the post being angular in cross section and having one of its flanges against the side of the post, and the other stop being in the general form of a channel embracing the post and extending on opposite sides thereof with the bottom of the channel forming a facing for the post, and the flanges of the channel extending on the sash guides of the post and formed with inturned flanges forming like sides of the sash guides and opposed to the other stop, means for securing the channel-shaped stop to the post. 95
10. In a window construction, the combination of a frame comprising a post having inner and outer stops on opposite sides thereof forming sash guides, sashes movable in the guides, one of the stops on each side of the post being angular in cross section and having one of its flanges against the side of the post, and the other stop being in the general form of a channel embracing the post and extending on opposite sides thereof with the bottom of the channel forming a facing for the post, and the flanges of the channel extending on the sash guides of the post and formed with inturned flanges forming like sides of the sash guides and opposed to the other stop, means for securing the channel-shaped stop to the post, and a channel-shaped facing strip embracing the opposite side of the post to that on which the channel-shaped stop is located, and having flanges overlying the other flanges of said angular stops. 100
11. In a window construction, the combination with a window frame, inner and outer stops forming a sash guide, and a sash movable in the guide; of spring means housed in one of the stops and arranged to press the stop against the sash in a direction at a right angle to the plane of the sash, and an adjusting screw connecting the spring means to the frame, said screw extending at a right angle to the plane of the sash and being located at one side of the point of engagement of the spring pressed stop and the sash, and beyond the plane of the edge of the sash. 115
